DAVID C. DINGER, OF WASHINGTON, DISTRICT OF COLUMBIA.

DETACHABLE WEIGHT FOR BASE-BALL BATS

1,030,982.

Specification of Letters Patent.

Patented July 2, 1912.

Application filed November 28, 1911. Serial No. 662,864.

To all whom it may concern:

Be it known that I, DAVID C. DINGER, a citizen of the United States, and residing in the city of Washington, in the District of Columbia, have invented certain new and useful Improvements in Detachable Weights for Base-Ball Bats, of which the following is a specification.

In the game of base-ball it has been found to be advantageous for the players to exercise, a short time before "going to the bat," with a bat or the like which is heavier than the one they intend to use in striking the ball. After exercising in such a manner a return to the use of a bat of a lighter weight gives the player a better control over said bat, and he is able to strike the ball with greater accuracy and ease.

Primarily, the object of this invention is to provide means for loading a base-ball bat so that the latter can be used for exercising purposes and for the usual function of striking a ball, thus permitting one bat to be used for both purposes which will greatly increase the player's control over the use of the same.

An additional object of this invention is to provide a weight embodying means to adapt the same to be applied to and removed from a base-ball bat without the employment of nails, screws or other fastenings of a permanent character, and which can be operated without being held in the hands.

Furthermore, the invention aims to provide a device for the purpose stated, the construction of which is such as to adapt it for application to different sizes of bats, the clamping means being adjustable, and thereby enable it to be used by a number of players without a change of any of its parts.

A further object of the invention is to provide a device for the purpose stated which can be easily and quickly attached to and detached from a base-ball bat, which when applied will be firmly held thereon until it is desired to remove same, which can be quickly and easily operated, and which will be economical in construction and the parts so arranged as to provide easy access for repair.

Having these general objects in view, and others which will appear as the nature of the invention is better understood, the invention consists substantially in the novel construction, combination and arrangements of the parts hereinafter described, illustrated

in the accompanying drawings, and pointed out in the appended claims.

In the drawings—Figure 1 is a vertical elevation of the invention showing a portion of the casing broken away, Fig. 2 is a plan view of said invention, and Fig. 3 is a detail of a shoe attached to an end of the clamping arm.

Similar reference characters refer to like parts throughout the drawings.

Referring in detail to the drawings, the numeral 1 designates the base on which the mechanism is supported. Positioned centrally on said base is a truncated cone-shaped member 2 having centrally therein a threaded orifice 3 in which a threaded spindle hereinafter described, operates. A ring-like member 4 having a threaded portion 5 thereon is formed on said base at the outer edge and provides engagement for the lower portion of a casing 6, similarly threaded. The said casing incloses the mechanism of the device to prevent injury to same, and is provided with a central opening in the top which acts as a guide when inserting the bat in the device. The cone-shaped member 2 and the ring 4 are formed integral with the base 1.

A movable plate 7 having a threaded spindle 8 adapted to operate in the threaded orifice 3, is positioned above the base 1, and upon rotation of said plate and spindle the former is raised or lowered with relation to said base. The plate 7 is provided with a plurality of slotted arms 8' in which clamping arms 9 are suitably pivoted on pins 10. The normal position of the arms 9 is relatively vertical and they oscillate on the pins 10 when moved in clamping the object. The upper face of said plate is provided with pointed lugs 11 which afford gripping means for the end of the bat when the same is inserted between the clamping arms for the purpose of rotating said plate.

The inner face 12 of the depending portion of the arms 9 is rounded to provide more perfect engagement with the surface of the cone-shaped member 2, and the outer face is provided with a recess 13 to receive a coiled spring 14 which embraces said lower portion of all the clamping arms and keeps the latter in close engagement with the cone member.

On the upper end of the arms 9 a shoe 15 is pivoted on a pin 16 passing through lugs 17, formed on the back of the shoe, and

said arm, as shown in the drawings. In said shoe and adjacent the lugs 17, a slot 18 is formed to allow an edge of the arm 9 to enter and provide free movement of said 5 shoe on the arm. A lug 19 is provided on the arm 9 below the pivotal point of said shoe to prevent the downward movement of the latter when the bat is inserted in the opening between the shoes.

10 The clamping face 20 of the shoe 15 is formed on the arc of a circle in order to provide engagement with the surface of the bat. The adjacent faces 21-21' of said shoe are provided with slots 22, in which the 15 ends of a band of felt or the like may be inserted and suitably clamped when it is desired to provide protecting means on the face of said shoe.

To limit the upward movement of the 20 plate 7, when the same is rotated, a washer 24 is attached to the end of the spindle 8 by means of a machine screw 25. A recessed portion 26 is formed in the bottom of the base 1 for the operation of said washer. The 25 bottom of the base 1 is serrated 27 as shown in Fig. 1 to prevent rotation of the device when the clamping mechanism is being operated. Additional lugs may be provided on said base to afford additional gripping 30 means.

The operation of the invention is as follows: The device is placed on the floor or ground and the lower portion of a base-ball bat is inserted between the clamping shoes 35 through the opening in the top of the casing until said portion comes into contact with the lugs 11 which will afford gripping means by which the plate 7 may be rotated when the bat is turned by the hands of the 40 operator or player. The rotation of the plate and spindle 8 in one direction causes the depending portion of the arms 9 to be forced away from the said spindle by reason of coming into contact with the surface of 45 the cone 2 and thereby the clamping shoes pivoted on the upper ends of the arms 9 are brought into close relation and embrace the portion of the bat to be clamped. The shoes 15 being pivoted to the arms 9 accommodate themselves to the contour of the bat. An additional turn is given to the bat that the 50 device may be firmly clamped thereon. The bat with this additional weight can then be used for exercising before the game.

55 When it is desired to release the device and use the bat for the usual function of striking the ball, the bat is turned in the opposite direction which causes the depending portion of the arms to approach the spindle 60 and thereby move the upper portion of said arms in the opposite direction and the shoes away from the surface of the bat. The

coiled spring 14 embracing the depending portion of the arms holds the latter in frictional engagement with the surface of the 65 cone at all times.

Having thus described the invention, what is claimed as new, and desired to be secured by Letters Patent, is:

1. A detachable weight for base-ball bats 70 comprising in combination, a plurality of members, means for causing said members to engage with the end portion of a bat, and means for actuating said last mentioned means. 75

2. A detachable weight for base-ball bats comprising in combination, a plurality of members, means for causing said members to engage with the end portion of a bat, means for actuating said last mentioned 80 means, and a guide for directing said portion to said members.

3. A detachable weight for base-ball bats comprising in combination, a base having a threaded hole therein, a member arranged to thread into said hole, a plurality of arms disposed on said member and arranged to clamp together when said member is threaded into said base. 85

4. A detachable weight for base-ball bats 90 comprising in combination, a base having a threaded hole therein, a member arranged to thread into said hole, a plurality of arms disposed on said member and arranged to clamp together when said member is 95 threaded into said base, and a plurality of adjustable shoes on said arms.

5. A detachable weight for base-ball bats comprising in combination, a base having a threaded hole therein, a member arranged 100 to thread into said hole, a plurality of arms disposed on said member and arranged to clamp together when said member is threaded into said base, a plurality of adjustable shoes on said arms, and means arranged to engage in the bat so that said member may be actuated rotatably thereby. 105

6. A detachable weight for base-ball bats comprising in combination, a base having a threaded hole therein, a member arranged 110 to thread into said hole, a plurality of arms disposed on said member and arranged to clamp together when said member is threaded into said base, a plurality of adjustable shoes on said arms, means arranged 115 to engage in said bat so that said member may be actuated rotatably thereby, and a casing for protecting said parts and for guiding a bat to said arms.
